Primary Examiner — Khawaja Anwar*Assistant Examiner* — Taylor O Mortorff(57) **CLAIM**

The ornamental design for a magnetic sweeper, as shown and described.

DESCRIPTION

FIG. 1 is a front perspective view of a magnetic sweeper, showing our new design;

FIG. 2 is a front plan view thereof;

FIG. 3 is a rear plan view thereof;

FIG. 4 is an enlarged top plan view thereof;

FIG. 5 is an enlarged bottom plan view thereof;

FIG. 6 is a left-side elevation view thereof;

FIG. 7 is a right-side elevation view thereof; and,

FIG. 8 is an exploded perspective view thereof, shown with environment.

The broken lines are directed to environment and are for illustrative purposes only; the broken lines form no part of the claimed design.

1 Claim, 8 Drawing Sheets(56)
